UNITED STATES PATENT OFFICE

2,288,852

PIANO ACTION

Francis C. Socin, St. Charles, Ill., assignor to The Rudolph Wurlitzer Company, Chicago, Ill., a corporation

Application October 13, 1941, Serial No. 414,749

3 Claims. (Cl. 84—240)

This invention relates to a piano action, particularly of the drop action type applicable to the small or spinet type of upright pianos, reference thereto being had to my Letters Patent No. 2,239,204, issued April 22, 1941, for "Upright piano."

The feature of the invention resides in the capstan screw and its association with the member operating to transmit motion between the piano key and the wippen. By means of the construction and relation of the capstan screw and motion transmitting member, the operative connection between the key and said member is substantially simplified, both from the standpoint of production, assembly and disassembly. Thus, each key is individually removed for adjustment or servicing without requiring removal of the action, and, on the other hand, the action itself may be conveniently removed without disturbing the associated key or member.

The full nature of the invention will be understood from the accompanying drawing and the following description and claims:

Fig. 1 is a sectional view through a piano action showing a unit thereof with its associated actuating piano key. Fig. 2 is an enlarged view of the capstan screw with a portion of the associated parts. Fig. 3 is a plan view of the structure shown in Fig. 2.

In the drawing there is shown a unit of a piano action including an action rail 10, frame structure 11, lower supporting rail 12 and upper rail 13, all associated and arranged in the usual manner with the piano strings 14.

The action is of the usual character embodying the hammer 15, with damper 16 and back check 17 supported upon a wippen 18. The wippen is fulcrumed at 19 on the rail 10 by the usual flange, and has pivotally mounted thereon the usual jack 20 for driving the hammer action 21.

Associated with such piano action there is provided the usual piano key 22 which is fulcrumed about the hinge pins 23 intermediate its ends upon the keyboard 24 mounted on the key bed 25.

The actuating end of said key is provided with the usual adjustable capstan screw 26 having a bearing head 27 formed on the upper end thereof. Extending upwardly from the bearing head there is provided a rigid retainer pin 28 which may be separately formed and inserted into said capstan screw, or, formed integral therewith. Said pin extends in alignment with the axis of the screw terminating in a free end at a distance thereabove.

Motion is transmitted between the action end of the key 22 and the wippen 18 through the medium of a rigid drop lever 29 which extends downwardly from the level of the key to the lower level of the wippen. The lower end of the drop lever is fashioned with a foot 30 extending forwardly thereof under and in alignment with the wippen for operative engagement with the underside thereof. The lower and forward end of the foot is pivotally connected through the link 31 with a flange secured to the lower supporting rail 12. The upper end of the drop lever is provided with a reversely directed finger 32 extending over the action end of the piano key 22. Said finger is provided with a bearing felt 33 arranged for bearing engagement upon the head 27 of the capstan screw. Said finger is also provided with an upwardly flared opening 34 for reception of the retaining pin 28.

By means of this construction, the key action is positively transmitted to the wippen and the piano action through elevation of the drop lever by the capstan screw, resulting in corresponding elevation of the wippen. To that extent, the capstan screw with its bearing head 27, performs its usual function. The retaining pin 28 extending rigidly upwardly from the bearing head of the capstan screw and in axial alignment therewith, serves to retain the drop lever in operative engagement with the piano key through the medium of said screw and the finger 32, while permitting angular movement therebetween. At the same time the character of the pin extending through the upwardly flared opening in the finger 32 permits the latter to be readily lifted over and off of the retaining pin when it is desired to remove the key.

From the foregoing description of this embodiment of the invention, the mode of operation, and advantages thereof will be readily understood, and while this invention is particularly designed and adapted for use in connection with small spinet types of upright pianos, it may be employed for transmitting actions in all types of pianos or similar instruments.

The invention claimed is:

1. In an upright piano, a hammer action mounted in front of the strings with a wippen disposed below the level of the keyboard and a key fulcrumed on said keyboard, a rigid drop lever extending downwardly from said key with its lower end in operative engagement with said wippen, said drop lever being provided at its upper end with a portion extending rearwardly over and in spaced relation to the action end of

said key formed with an upwardly flaring opening therein, a capstan screw adjustably mounted on said key provided with a bearing head engageable with said rearwardly extending portion concentrically with the opening therein, and a retaining pin on said screw extending upwardly from the head thereof through the opening in said rearwardly extending portion for removably retaining the same in operative engagement with said bearing head.

2. In an upright piano, a hammer action mounted in front of the strings with a wippen disposed below the level of the keyboard and a key fulcrumed on said keyboard, a rigid drop lever extending downwardly from said key with its lower end in operative engagement with said wippen, said drop lever being provided at its upper end with a portion extending rearwardly over and in spaced relation to the action end of the key, a capstan screw adjustably mounted on the action end of said key extending therefrom for engagement with said rearwardly extending portion, a retaining pin on said capstan screw extending upwardly therefrom into said rearwardly extending portion for permitting motion to be transmitted thereto by said capstan screw while retaining the same in bearing relation thereon, and a guiding link having one end thereof pivotally anchored on said hammer action and the

free end thereof pivotally connected with the lower end of said drop lever for maintaining it in operative alignment with said key and wippen.

3. In an upright piano, a hammer action mounted in front of the strings with a wippen disposed below the level of the keyboard and a key fulcrumed on said keyboard, a rigid drop lever extending downwardly from said key with its lower end in operative engagement with said wippen, said drop lever being provided at its upper end with a portion extending rearwardly over and in spaced relation to the action end of said key formed with an upwardly flaring opening therein, a capstan screw adjustably mounted on said key provided with a bearing head engageable with said rearwardly extending portion concentrically with the opening therein, a retaining pin on said screw extending upwardly from the head thereof through the opening in said rearwardly extending portion for removably retaining the same in operative engagement with said bearing head, and a guiding link having one end thereof pivotally anchored on said hammer action and the free end thereof pivotally connected with the lower end of said drop lever for maintaining it in operative alignment with said key and wippen.

FRANCIS C. SOCIN.
